UNITED STATES PATENT OFFICE.

ANDREW BACHLE, OF DETROIT, MICHIGAN.

MANIFOLD FOR INTERNAL-COMBUSTION ENGINES.

1,397,482.

Specification of Letters Patent. Patented Nov. 15, 1921.

Application filed November 15, 1919. Serial No. 338,167.

To all whom it may concern:

Be it known that I, ANDREW BACHLE, a citizen of the United States of America, residing at Detroit, in the county of Wayne 5 and State of Michigan, have invented certain new and useful Improvements in Manifolds for Internal-Combustion Engines, of which the following is a specification, reference being had therein to the accompanying drawings.

The invention relates to manifolds for internal combustion engines of that type in which the cross-sectional area of the manifold is varied to produce a throttling effect 15 and to maintain the velocity of the gases. The present invention comprises the novel construction of the means for varying the cross-section of the manifold, and further in the combination of the inlet and exhaust 20 manifolds in one structure as hereinafter set forth.

In the drawings:

Figure 1 is a sectional side elevation of a portion of the manifold constructed in accordance with my invention;

Figs. 2, 3 and 4 are cross-sections, respectively, on lines 2—2, 3—3 and 4—4 of Fig. 1.

In the usual construction of inlet manifolds for internal combustion engines, the 30 cross-sectional area of the conduit is fixed and the volume of gas passing therethrough is controlled by a throttle. This has the disadvantage of greatly decreasing the velocity of the gases in their passage through the 35 manifolds when the throttle is partially closed. On the other hand, by varying the cross-sectional area of the intake uniformly throughout its extent, the volume of gas may be controlled without greatly reducing 40 the velocity.

With the present invention the variation in the area of the inlet is accomplished by a simple easily manipulated mechanical construction. In detail, A is a manifold, preferably embodying one integral construction, an exhaust portion B and an inlet portion C. The inlet portion is in the form of a straight cylinder D standing adjacent to the several ports E leading into the engine cylinders and also adjacent to the common inlet port F connecting with the carburetor. 50

Within the cylinder D is placed a segmental abutment G which is secured by suitable means such as the screws H passing 55 through apertured bosses I at one side of the cylinder. J is a rock shaft extending

completely through the cylinder coaxially therewith, and K is a segmental wing secured to the shaft J by suitable means such as the screws L. The shaft J is journaled 60 in bearings M in end caps N which close the ends of the cylinder. One end of the shaft is connected with the lever arm O by means of which the shaft may be rotated in various positions of adjustment.

With the construction as described, in operation, when the shaft is in a position, shown in Fig. 2, the wing K is in close proximity to the abutment G so as to produce a passage of restricted cross sectional area 70 throughout the manifold. This passage is, however, in communication with both the inlet port F from the carburetor and the several ports E leading into the engine cylinders so that the gas will pass at uniform 75 velocity but in restricted volume to the cylinders. To increase the power the shaft J is rocked through the medium of the arm O swinging the wing K to enlarge the passage for the gas. In this way the manifold 80 may be enlarged in cross-sectional area to its maximum capacity where the wing comes in contact with the abutment G.

The inlet manifold being integral with the exhaust manifold, the outer wall of the inlet 85 manifold will be heated which will facilitate the complete vaporization of the liquid fuel. Over-heating is avoided chiefly by reason of the fact that the gas passes through the manifold at high velocity, but if any of the 90 liquid is deposited on the walls, it will quickly be converted into vapor.

What I claim as my invention is:

1. An inlet manifold for internal combustion engines, comprising a cylindrical conduit, a stationary partition therein, and a member rotatably adjustable with respect to said stationary partition for enlarging and diminishing the cross-sectional area of said conduit, the axis of rotation of said member 95 extending longitudinally of said cylindrical conduit.

2. An inlet manifold for internal combustion engines, comprising a cylindrical conduit, a shaft extending axially through said conduit, a stationary partition extending from the wall of said conduit to said shaft, and a wing secured to said shaft and extending to the periphery of said conduit, said shaft and wing being rotatably adjustable to enlarge or diminish the cross-sectional area of the conduit.

3. An inlet manifold for internal combustion engines, comprising a cylindrical conduit, provided with an inlet port and a plurality of ports connected laterally therewith and to the respective cylinders of the engine, a rotative shaft extending axially through said cylindrical conduit, a wing attached to said shaft and extending to the periphery of the conduit, a stationary partition extending from the conduit to said shaft, and means for adjusting said shaft and wing relative to said stationary partition to enlarge or diminish the cross-sectional area of the conduit which is in communication with said inlet and cylinder ports.

4. A manifold for internal combustion engines having an exhaust passage therein and a cylindrical inlet passage, the latter being provided with an inlet port and a plurality of cylinder-connecting ports, a rotative shaft extending axially through said cylindrical

conduit, a wing secured to said shaft and extending to the periphery of the conduit, a partition extending from said conduit to said shaft, and means for rotatively adjusting the shaft and wing to enlarge or diminish the cross-sectional area of the conduit which is in communication with said ports.

5. A manifold for internal combustion engines, comprising a cylindrical conduit having open ends, caps for closing said ends, a shaft extending axially through said conduit and journaled in said caps, a segmental wing secured to said shaft and extending to the cylinder wall of the conduit, a segmental stationary partition secured to the wall of the conduit and extending through said shaft, and means for rotatively adjusting said shaft to enlarge or diminish the cross-sectional area of said conduit.

In testimony whereof I affix my signature.

ANDREW BACHLE.
